OF ESMOND, RHODE ISLAND, A CORPORATION OF RHODE ISLAND

LOOM AND PROCESS OF WEAVING

Application filed April 26, 1928. Serial No. 273,006.

This invention pertains to the manufacture of textile fabrics and more particularly to a method of and apparatus for weaving. There is at present a very considerable demand for woven blankets and similar wide fabrics of solid color (except possibly for transverse stripes near the ends) having a single centrally disposed medallion-like figure or panel which in whole or in part is of a color or material contrasting with the solid body color. This medallion or figure may be purely ornamental or consist of the coat of arms, name, or other distinguishing mark of a club, hotel, camp, or other establishment, and is usually produced by weaving in a weft of the proper color or material in accordance with the desired pattern. If single fabric is being woven, the body wefts are all carried to the back of the fabric and floated while the figure weft is being interwoven with the warps, or if double fabric is being woven, as for example, in a blanket, the back body weft may be floated across the figure while the front body weft may continue to weave, but is carried to the back or in front of the figure weft in accordance with the requirement of the pattern. Whatever the type of body weave, the figure weft is usually floated from the selvage inwardly to the border of the figure, and in the finishing operation these floats of the figure weft are trimmed off. In weaving relatively narrow fabrics; when the medallion or panel is nearly as wide as the fabric; or when the weft is of cheap material; the above usual method is sufficiently good, but when the fabric is wide and the medallion occupies a relatively small portion of its width, and particularly if the figure weft be of expensive material, such for example as wool or silk, the usual process is very wasteful and unduly expensive, since the long weft floats must be trimmed off and sold as waste at a price usually much lower than the cost of the raw material from which they were spun.

In order to avoid such unnecessary waste of material, and to reduce the labor and cost of finishing fabrics of the class described, I have devised a method of weaving in which the floats in the figure weft are reduced very

nearly to a minimum, thus avoiding excessive waste and facilitating the finishing operation, and for carrying this new method into effect I have provided effective means which accomplishes the desired result without complicating the loom structure to any substantial extent, without interfering with the orderly and usual operation of the loom parts, and employing simple mechanical expedients which can be incorporated in the loom at small cost and without difficulty.

It is usual in broad looms, such as are used for weaving blankets and similar fabrics, to place the weft fork or detector near the center of width of the loom, but I have found in weaving medallion-like figures in accordance with my improved method and employing the usual shuttle having its eye near one end, that the weft fork often operates to stop the loom even though the weft is unbroken and has not been exhausted. A careful study indicates that the improper response of the weft fork under such circumstances is due to the fact that the float thread extending from one of the looper pins which I provide, as herein-after more fully described, to the eye of the shuttle, is longer than the float reaching from the other looper pin to the shuttle eye, this difference in length being substantially equal to the length of the shuttle. In broad looms using a heavy weft as for blanket weaving, the shuttle is usually from 18 to 24 inches in length. If the weft fork is set to remain inactive when engaged by the shorter run of yarn extending from one looper pin to the shuttle eye, I find that it may, and frequently does, respond to the relatively slacker and longer run of yarn extending from the other looper pin to the shuttle eye.

To avoid this difficulty I have adopted the expedient of placing the shuttle eye substantially at the center of length of the shuttle, thus obtaining a substantially equal run of yarn from each looper pin to the shuttle eye so that the tension is uniform and the weft fork may readily be adjusted to respond only to yarn breakage, exhaustion, or abnormally slack tension.

While I have referred to the weaving of blankets as illustrative of one specific field

of utility of my invention, I do not wish to confine myself to such particular use, since the invention is of broad application to the art of weaving. Furthermore, the invention is applicable to the production of intricate designs and is not necessarily limited to the production of a single figure or medallion midway between the edges of the fabric, but for convenience in illustration I have herein shown it as applied to the weaving of a centrally disposed medallion of geometrical design consisting of a single contrasting color upon a single weave body fabric of another color.

15 In the accompanying drawings I have illustrated one desirable embodiment of means useful in performing my improved process, showing such means in its relation to well-known parts of a loom, and I have also indicated diagrammatically certain steps in the formation of such a solid geometrical figure as above referred to, but I wish it to be understood that the drawings are merely by way of example and that the improved process 25 may doubtless be carried into effect by other specific means than as herein disclosed. In the drawings.

Fig. 1 is a fragmentary diagrammatic end elevation of a loom structure of usual type, 30 partly in vertical section, showing the relation of my improved apparatus to the breast beam and lay;

Fig. 2 is a fragmentary front elevation, with certain parts in section and parts broken 35 away, showing the lay of the loom to larger scale than in Fig. 1, and with my present apparatus applied thereto, the lay being indicated in its rearmost position;

Fig. 3 is a fragmentary view similar to 40 Fig. 2 but showing only the left hand part of the lay, and indicating the position of the parts when the lay has nearly completed its forward beat, a part of a cam carried by the breast beam being shown in section;

45 Fig. 4 is a fragmentary plan view, partly in section on the line 4—4 of Fig. 2;

Figs. 5 to 10 are diagrammatic plan views illustrating several steps in my improved process;

50 Fig. 11 is a similar view showing the appearance of fabric made in accordance with the present process; and

Fig. 12 is a view similar to Fig. 11, showing the central medallion replaced by a border stripe.

Referring to the drawings numeral 1 designates the forward portion of a loom frame having the breast beam 2, the lay 3, the reed 4, the harness 5, and the cloth beam 6. Referring to Fig. 5, the selvage warps of the body fabric are indicated at W and W¹ respectively, it being understood that a sheet of warps extends in usual manner from one selvage to the other and that at the part of the fabric at 65 which the figure is to be formed, usually at

the center, a certain group of warp threads indicated at W² are selected to take part in the weaving of the figure. As shown in Fig. 5, the warps W³ and W⁴ are the selvage or border warps of the figure for any selected 70 pick, and if the figure be of uniform width throughout these same warps may constitute the selvages of the figure during the entire operation. However, if the figure varies in width, different warps will from time to time 75 form the selvage warps of the figure and to this end the figure warps of the group W² may be controlled by any suitable pattern mechanism as for example a jacquard or a dobby.

80 At a point about midway of the width of the loom, a weft detector D of any usual type is arranged, such detector remaining inactive so long as the weft is unbroken and under proper tension, but operating to initiate stoppage of the loom upon breakage or exhaustion of the weft or abnormal slack in the weft.

85 The body weft is indicated 7 in Fig. 5 and for illustrative purposes this weft may be considered to be of uniform color and material throughout the formation of the blanket or other article which is being woven. During the formation of the main part of the blanket, this body weft 7 interweaves with the warps 95 across the entire width of the fabric, but during the weaving of the figure, these body wefts are caused to float between the selvage warps W³ and W⁴ of the figure. That is to say, the body wefts do not weave with the figure warps, if single fabric is being woven,—all of the weft in such case being floated at the back of the fabric across the figure, but if double fabric is being woven, the rear body weft only may be floated, the body 100 weft which ordinarily forms the front face of the fabric being transferred to the rear face, if the figure is to have a solid color, or alternating with the figure weft in accordance with any desired pattern if the figure 105 is not of plain color.

110 Referring particularly to Figs. 2, 3 and 4, the lay is provided with brackets 8 and 8^a on its forward face, such brackets providing guideways for vertically movable looper pins 9 and 10 respectively. These looper pins are disposed between the selvages W and W¹ of the body fabric and the adjacent borders of the figure respectively. That is to say, as indicated in Fig. 5, the pins 9 and 10 are between the warps W and W³, and W⁴ and W¹, respectively, and these pins are preferably quite close to the outermost warps of the group W². While it is preferred to mount the pins 9 and 10 in brackets as shown, it is conceivable that they may be mounted in other ways and I do not wish to limit myself to the particular arrangement herein disclosed.

115 The pins 9 and 10 are pivotally secured at their lower ends to actuating levers 12 and 13 120

respectively. The lever 12 is fulcrumed upon a pin 14 carried by a bracket 15 depending from the lay, and a spring 16 acting upon the lever 12, tends to hold the pin 9 normally in its uppermost position. The pin 10 is likewise held normally in uppermost position by a similar spring not shown, it being understood that the lever 13 is supported in the same way as the lever 12. Preferably the levers 12 and 13 are provided with a stop 16^a engageable with the lay to limit the upward movement of the pins 9 and 10. Each of the levers 12 and 13 is furnished at its free end with a cam follower roll 17, and these cam follower rolls are adapted, as the lay beats forward, to engage stationary cams 20 mounted upon brackets 19 secured to the breast beam. Preferably each of these cams 20 comprises an active portion 21, and intermediate or dwell portion 22, and a second active portion 23.

On the other hand, in accordance with the present invention, and as shown in Fig. 11, the blanket 30 having the selvages 31 and 32, is provided with the central figure or medallion 33, but in this case the floats of figure yarn, indicated at 34 and 35, extend outwardly only part way from the borders of the figure toward the selvages of the fabric. This not only saves a large amount of yarn, but facilitates the finishing operation, since the outer ends of these floats are not engaged with the selvage of the body fabric, and thus need not be picked out, saving time and lessening danger of injury to the fabric.

Referring to Figs. 5 to 10 inclusive, my novel method of weaving is illustrated diagrammatically as embodying the following steps: in Fig. 5 the body wefts are shown at 37 and a portion of the figure or medallion is shown at 33. The last laid pick of filling in the pattern is indicated at 36 and from the right hand margin of the figure this filling yarn 37 extends to the eye E of the shuttle S, it being assumed that during the passage of the shuttle from the right hand border of the figure to the selvage of the fabric, the body warps between these points have been raised so that the filling 37 does not interweave therewith. After this pick of filling has been laid, one or more picks of the body weft carried, in a second shuttle S¹ may be laid to provide body fabric at the opposite side of the figure, it being understood that this body weft interweaves with the warps at the opposite sides of the figure but floats across the figure warps.

The shuttle S now travels across the loom to the left, as indicated in Fig. 6, and in so doing it wraps the figure weft 37 about the pin 10. That portion 38 of the figure weft which extends across the figure warps W² is interwoven with the latter, while the part 39 of the figure weft floats freely between the left hand margin of the figure and the left

hand selvage warp W. As the lay beats forward to beat up this last-named pick 38 of figure weft, the cam follower rolls 17 engage the risers 21 of the cams 20 and gradually retract the pins 9 and 10, the pin 9 at this time being idle. When the cam follower rolls 17 reach the dwell 22 of the cams, the pins 9 and 10 are held in the partly retracted position indicated in Fig. 3, so as still to retain the portion 37 of the filling and maintain the necessary tension upon the pick 38 for a proper laying of this pick into the fell of the cloth until the lay has almost reached the end of the forward beat, thereupon the cam followers 17 engage the second active portion 23 of the cams 20, thus fully retracting the pins 9 and 10 and releasing the loop 37 of the figure weft. Thus as the beat up of the lay is completed, the pick 38 of filling is beaten into the fell of the cloth, leaving a loop constituted by parts 37 of the filling weft, projecting from the right hand edge of the figure. The legs of this loop are thus both united to the material at the border of the figure, while the closed portion or bend of the loop is spaced from the edge of the figure a distance substantially equal to the distance of the pin 10 from such edge. As the pin 10 may be placed quite close to the border of the figure it is evident that the extending loop of figure filling may be relatively short as compared with the entire distance between the border of the figure and the selvage of the fabric.

The lay now beats back again, and the pins 9 and 10 are raised by the springs 16. One or more picks of body filling may now be laid, and then the shuttle S starts back toward the right hand side of the loom. The result being that the portion 39 of the filling, extending between the left hand border of the figure and the shuttle, is carried around the pin 9, providing the portion 40 of figure filling which is interwoven with the figure warps, and the float portion 41 extending from the right hand border of the figure to the shuttle. When now the lay beats up, the pins 9 and 10 are retracted at the end of the beat up of the lay, leaving the portion 39 of the filling to form a short loop at the left hand border of the figure. Repetitions of the above cycles of operation are indicated in Figs. 9 and 10, wherein there is indicated the gradual building up of the central medallion or panel.

By providing the shuttle S with an eye E in the center, it is clear that the run of filling extending at the end of any pick from the shuttle to one of the pins 9 or 10 respectively, is always equal to that at the end of any other pick, and it is thus possible to adjust the detector D in such a way that it will respond very sensitively to any abnormal slack in the filling tension, but without danger of improper response due to inequality in the length

of the yarn float at the completion of successive picks.

While I have herein illustrated retractable pins 9 and 10 as a means for retaining the 5 yarn loops, I wish it to be understood that such pins are merely representative of any suitable form of retaining means, and that such pins may be replaced by other and equivalent retaining devices without departing 10 from the spirit of the invention.

In the above description reference has been made particularly to the formation of a centrally disposed figure but in its broader aspect the invention has other utility, as for example in weaving patterns such as shown in Fig. 15 12 wherein the body fabric 40 has the selvages 41 and 42, and a color stripe 43 extending along the left hand selvage. For weaving such a fabric, a single one of the pins 9 above- 20 described may be employed. This pin retains loops 44 of the figure or striping filling so that it is not necessary to waste the filling which would ordinarily extend from the right hand border of the stripe to the right hand selvage 25 42. Doubtless the fundamental principle of the present invention may find other utilities in the art of weaving figure fabrics, and I contemplate that all such utilities fall within the scope of the invention as hereinafter 30 claimed.

While, for convenience in illustration and description I have shown a very simple geometrical figure in the center of the fabric, the invention is equally applicable to the production 35 of more complicated figures involving the use of several color wefts or wefts of different material and interweaving of certain portions of the body fabric with the figure weft. Furthermore the body fabrics need 40 not be of a plain or solid color or material, but may be woven in accordance with any desired pattern and by the use of usual pattern mechanism such for example as a jacquard.

I claim:

45 1. That method of weaving fabric having a figure intermediate its edges which comprises as steps interweaving a body-weft with the warp in forming the body of the fabric, floating said body-weft between the borders of the 50 figure, interweaving a figure-weft with those warps only which are within the confines of the figure, and causing the figure-weft to form float-loops which extend laterally from the border of the figure and terminate at 55 points intermediate such border and the selvage of the fabric.

2. That method of weaving fabric having a figure intermediate its edges which comprises as steps interweaving a body-weft with the 60 warp in forming the body of the fabric, floating said body-weft between the borders of the figure, interweaving a figure-weft with those warps only which are within the confines of the figure, thereby causing successive picks 65 of the figure-weft to form floats extending

from the border of the figure, said floats being wholly free from the fabric except at the border of the figure.

3. That method of weaving fabric having a figure intermediate its edges which comprises as steps interweaving a body-weft with the warp in forming the body of the fabric, floating said body-weft between the borders of the figure, and interweaving a figure-weft with those warps only which are within the 75 confines of the figure, thereby causing the figure-weft to form laterally extending float-loops, the legs of each loop being united to the fabric at the border of the figure and the bends of the loops being wholly free. 80

4. That method of weaving fabric having a figure intermediate its edges which comprises as steps interweaving a body-weft with the warp in forming the body of the fabric, floating said body-weft between the borders 85 of the figure, interweaving a figure-weft with those warps only which are within the confines of the figure, the figure-weft floating beyond the lateral borders of the figure, detaining the figure-weft adjacent to the point 90 at which it begins to interweave with the figure-warp, at each pick of the shuttle, to form a float-loop, and releasing each loop so formed upon the completion of the next beat-up of the lay. 95

5. That method of weaving fabric having a figure intermediate its edges which comprises as steps interweaving a body-weft with the warp in forming the body of the fabric, floating said body-weft between the borders of the figure, interweaving a figure-weft with those warps only which are within the 100 confines of the figure, the figure-weft floating beyond the lateral borders of the figure, and temporarily detaining the floating figure-weft between each pair of successive picks thereof at points intermediate the borders 105 of the figure and the selvages of the fabric whereby to form float-loops extending from the borders of the figure, part way to the 110 respective selvages.

6. That method of weaving fabric having a figure intermediate its edges which comprises as steps interweaving a body-weft with the warp in forming the body of the fabric, floating said body-weft between the borders of the figure, interweaving a figure-weft with those warps only which are within the 115 confines of the figure, the figure-weft floating beyond the lateral borders of the figure, engaging the floating figure-weft resulting from successive picks thereof with means for temporarily retaining said floating-weft to form a loop extending laterally from the border of the figure, and thereafter disengaging the retained loop from said retaining means. 120

7. That method of weaving fabric having a figure intermediate its edges which comprises as steps interweaving a body-weft 125

with the warp in forming the body of the fabric, floating said body-weft between the borders of the figure, interweaving a figure-weft with those warps only which are within the 5 confines of the figure, the figure-weft floating beyond the lateral borders of the figure, providing retaining means upon the lay of the loom at points intermediate the selvage warps and the outermost figure-warp respectively, causing the floating figure-wefts 10 resulting from successive picks thereof to be detained by one of said retaining means, thereby to form a float-loop, and releasing each loop thus formed upon the next beat-up 15 of the lay.

8. That method of weaving fabric having a figure intermediate its edges which comprises as steps interweaving a body-weft with the warp in forming the body of the 20 fabric, floating said body-weft between the borders of the figure, interweaving a figure-weft with those warps only which are within the confines of the figure, the figure-weft floating beyond the lateral borders of the figure, 25 and causing the floating figure-weft resulting from successive picks thereof to wrap around retaining means disposed intermediate the border of the figure and the selvage of the fabric thereby forming float loops attached 30 to the fabric only adjacent to the border of the figure.

9. That method of weaving fabric having a figure intermediate its edges which comprises as steps interweaving a body-weft 25 with the warp in forming the body of the fabric, floating said body-weft between the borders of the figure, interweaving a figure-weft with those warps only which are within the confines of the figure, the figure-weft 40 floating beyond the lateral borders of the figure, and causing the floating figure-weft resulting from successive picks thereof to wrap around retractable retaining means disposed intermediate the border of the figure and the selvage of the fabric, and thereafter 45 retracting said retaining means to release the figure-weft float.

10. That method of weaving fabric having a figure intermediate its edges which comprises as steps interweaving a body-weft with the warp in forming the body of the fabric, floating said body-weft between the borders of the figure, interweaving a figure-weft 50 with those warps only which are within the confines of the figure, the figure-weft floating beyond the lateral borders of the figure, providing a retractable retaining pin on the lay of the loom between each selvage warp and the outermost figure warp, causing the 55 figure-weft at each pick thereof to wrap about one of said pins immediately before it interweaves with the figure-warp, and retracting said pin to release the detained weft 60 as the lay beats up following each pick.

65 11. Apparatus of the class described for

weaving fabric having a medallion-like figure intermediate its selvages, said apparatus including a figure weft shuttle which moves from one selvage to the other of the fabric and comprising means for interweaving a 70 body weft with warps in forming a body fabric and for floating said body-wefts between the borders of the figure and means for engaging the figure-weft with those warps 75 only which are within the confines of the 75 figure.

12. In combination in a weaving loom having a lay, a pick forming means, and warp shedding means, means for actuating the shedding means and pick forming means to 80 interweave a body-weft with the warp in forming a body fabric and to float said body-weft across certain warp threads in forming a figure, and for interweaving a figure-weft with said certain warp threads alone 85 to form the figure, the figure-weft floating beyond the lateral borders of the figure, and means interposed between the selvage of the fabric and the border of the figure for temporarily engaging the floating figure-weft 90 thereby to form loops whose closed ends are free from the fabric.

13. In combination in a weaving loom having a lay, a pick forming means, and warp shedding means, means for actuating the 95 shedding means and pick forming means to interweave a body-weft with the warp in forming a body fabric and to float said body-weft across certain warp threads in forming a figure, and for interweaving a figure-weft 100 with said certain warp threads alone to form the figure, the figure-weft floating beyond the lateral borders of the figure, and means engaging the figure-weft to form float-loops 105 whose legs are united to the fabric at the border of the figure and whose bends are wholly free from the fabric.

14. In combination in a weaving loom having a lay, a pick forming means, and warp shedding means, means for actuating the 110 shedding means and pick forming means to interweave a body-weft with the warp in forming a body fabric and to float said body-weft across certain warp threads in forming a figure, and for interweaving a figure-weft 115 with said certain warp threads alone to form the figure, the figure-weft floating beyond the lateral borders of the figure, and means engaging the figure-weft floats to form loops 120 which are wholly free from the fabric except at the border of the figure.

15. In combination in a weaving loom having a lay, a pick forming means, and warp shedding means, means for actuating the 125 shedding means and pick forming means to interweave a body-weft with the warp in forming a body fabric and to float said body-weft across certain warp threads in forming a figure, and for interweaving a figure-weft 130 with said certain warp threads alone to form

the figure, the figure-weft extending beyond the lateral borders of the figure in the form of loops free at one end, and means, disposed intermediate the selvage warps and the border of the figure, about which the figure-weft is wrapped between successive picks.

16. In combination in a weaving loom having a lay, a pick forming means, and warp shedding means, means for actuating the shedding means and pick forming means to interweave a body-weft with the warp in forming a body fabric and to float said body-weft across certain warp threads in forming a figure, and for interweaving a figure-weft with said certain warp threads alone to form the figure, the figure-weft floating beyond the lateral borders of the figure, and being attached to the fabric only at the border of the figure, and means engaging the figure-weft floats to form loops thereof extending from the borders of the figure and terminating at points intermediate such borders and the selvages of the fabric.

17. In combination in a weaving loom having a lay, a pick forming means, and warp shedding means, means for actuating the shedding means and pick forming means to interweave a body-weft with the warp in forming a body fabric and to float said body-weft across certain warp threads in forming a figure, and for interweaving a figure-weft with said certain warp threads alone to form the figure, the figure-weft floating beyond the lateral borders of the figure, and means for temporarily detaining the floating figure-weft resulting from successive picks thereof whereby to form a float-loop extending laterally from the border of the figure, and for releasing the retained loop just prior to the end of the following beat-up of the lay.

18. In combination in a weaving loom having a lay, a pick forming means, and warp shedding means, means for actuating the shedding means and pick forming means to interweave a body-weft with the warp in forming a body fabric and to float said body-weft across certain warp threads in forming a figure, and for interweaving a figure-weft with said certain warp threads alone to form the figure, the figure-weft floating beyond the lateral borders of the figure, and retaining means upon the lay at a point intermediate the selvage warp and the adjacent figure-warp for detaining a loop of the figure-weft between successive picks thereof while the figure-weft is being interwoven with the figure-warps, said means releasing the figure-weft on the next beat-up of the lay.

19. In combination in a weaving loom having a lay, a pick forming means, and warp shedding means, means for actuating the shedding means and pick forming means to interweave a body-weft with the warp in forming a body fabric and to float said body-

figure, and for interweaving a figure-weft with said certain warp threads alone to form the figure, the figure-weft floating beyond the lateral borders of the figure, means carried by the lay for engaging the floating figure-weft resulting from successive picks whereby to retain said floating weft in the form of a loop extending laterally from the border of the figure, and means operative as the lay completes its beat-up movement for releasing the retained loop.

20. In combination in a weaving loom having a lay, a pick forming means, and warp shedding means, means for actuating the shedding means and pick forming means to interweave a body-weft with the warp in forming a body fabric and to float said body-weft across certain warp threads in forming a figure, and for interweaving a figure-weft with said certain warp threads alone to form the figure, the figure-weft floating beyond the lateral borders of the figure, and retractable means, disposed intermediate the selvage of the fabric and the border of the figure, about which the figure-weft is wrapped between successive picks, said retractable means being retracted at each beat of the lay to release the figure-weft.

21. In combination in a weaving loom having a lay, a pick forming means, and warp shedding means, means for actuating the shedding means and pick forming means to interweave a body-weft with the warp in forming a body fabric and to float said body-weft across certain warp threads in forming a figure, and for interweaving a figure-weft with said certain warp threads alone to form the figure, the figure-weft floating beyond the lateral borders of the figure, vertically movable pins at opposite sides respectively of the group of figure-warps, each pin normally being so positioned that the figure-weft wraps about it just prior to interweaving with the figure-warps, and means for retracting each pin from the float wrapped around it as the lay completes its beat-up movement.

22. In combination in a weaving loom having a lay, a pick forming means, and warp shedding means, means for actuating the shedding means and pick forming means to interweave a body-weft with the warp in forming a body fabric and to float said body-weft across certain warp threads in forming a figure, and for interweaving a figure-weft with said certain warp threads alone to form the figure, the figure-weft floating beyond the lateral borders of the figure, a pair of vertically movable pins mounted upon the lay forward of the shuttle path and disposed respectively at opposite sides of the group of figure-warps, means normally holding the said pins in uppermost position, and means, including a cam, for moving said pins downwardly as the lay beats-up.

23. In combination in a weaving loom hav-

ing a lay, a pick forming means, and warp shedding means, means for actuating the shedding means and pick forming means to interweave a body-weft with the warp in forming a body fabric and to float said body-weft across certain warp threads in forming a figure, and for interweaving a figure-weft with said certain warp threads alone to form the figure, the figure-weft floating beyond the lateral borders of the figure, a pair of vertically movable pins carried by the lay, said pins being at opposite sides respectively of the group of figure-warps, each pin normally being so positioned that the figure-weft wraps about it just prior to interweaving with the figure-warps, and means for partially retracting the pin while permitting it to retain the weft during the forward beat of the lay, and for completing the retraction of the pin to release the weft just before the end of the forward beat of the lay.

24. In combination in a weaving loom having a lay, a pick forming means, and warp shedding means, means for actuating the shedding means and pick forming means to interweave a body-weft with the warp in forming a body fabric and to float said body-weft across certain warp threads in forming a figure, and for interweaving a figure-weft with said certain warp threads alone to form the figure, the figure-weft floating beyond the lateral borders of the figure, a pair of vertically movable pins mounted in guides at the forward face of the lay and disposed respectively at opposite sides of the group of figure-warps and between the latter and the respective selvages of the fabric, springs tending to hold said pins in uppermost position, a lever connected to each pin, and stationary cams engageable by said levers as the lay beats-up for retracting the pin.

25. In combination in a weaving loom having a lay, a pick forming means, and warp shedding means, means for actuating the shedding means and pick forming means to interweave a body-weft with the warp in forming a body fabric and to float said body-weft across certain warp threads in forming a figure, and for interweaving a figure-weft with said certain warp threads alone to form the figure, the figure-weft floating beyond the lateral borders of the figure, a pair of vertically movable pins mounted in guides at the forward face of the lay and disposed respectively at opposite sides of the group of figure-warps and between the latter and the respective selvages of the fabric, springs tending to hold said pins in uppermost position, and means for retracting said pins in two stages as the lay beats-up.

26. In combination in a weaving loom having a lay, a pick forming means, and warp shedding means, means for actuating the shedding means and pick forming means to interweave a body-weft with the warp in

forming a body fabric and to float said body-weft across certain warp threads in forming a figure, and for interweaving a figure-weft with said certain warp threads alone to form the figure, the figure-weft floating beyond the lateral borders of the figure, a pair of vertically movable pins mounted in guides at the forward face of the lay and disposed respectively at opposite sides of the group of figure-warps and between the latter and the respective selvages of the fabric, springs tending to hold said pins in uppermost position, and cams means for retracting said pins part way during the forward beat of the lay, and for completing the retraction of the pins just before the lay completes its forward movement.

27. In combination in a weaving loom having a lay, a pick forming means, and warp shedding means, means for actuating the shedding means and pick forming means to interweave a body-weft with the warp in forming a body fabric and to float said body-weft across certain warp threads in forming a figure, and for interweaving a figure-weft with said certain warp threads along to form the figure, the figure-weft floating beyond the lateral borders of the figure, a pair of vertically movable pins mounted in guides at the forward face of the lay and disposed respectively at opposite sides of the group of figure-warps and between the latter and the respective selvages of the fabric, springs tending to hold said pins in uppermost position, and a stepped cam for retracting each pin, said cams retracting the pins part-way immediately after passage of the weft through the shed, permitting the pins to dwell, and then completing the retraction of the pins as the lay completes its forward movement.

28. In combination in a weaving loom having a lay, shuttles, and warp shedding means, means for actuating the shedding means and shuttles to interweave a body-weft with the warp in forming a body fabric and to float said body-weft across certain warp threads in forming a medallion-like figure, and for interweaving a figure-weft with said certain warp threads alone to form the figure, the figure-weft floating beyond the lateral borders of the figure in the form of loops free at one end at least from the fabric, a weft detector disposed substantially midway between the selvages of the fabric, and retractable pins for temporarily detaining said loops so as to insure substantially equal tension of figure-weft floats extending from either border of the figure to the figure-weft shuttle.

29. In combination in a weaving loom having a lay, shuttles, and warp shedding means, means for actuating the shedding means and shuttles to interweave a body-weft with the warp in forming a body fabric and to float said body-weft across certain warp threads

in forming a medallion-like figure, and for interweaving a figure-weft with said certain warp threads alone to form the figure, means for temporarily detaining the figure-wefts floating beyond the lateral borders of the figure in the form of loops whose closed ends are free from the fabric, and a weft detector disposed substantially midway between the selvages of the fabric, the shuttle for the figure-weft having a centrally disposed delivery eye.

30. In combination in a weaving loom having a lay, and warp shedding means, means for actuating the loom to interweave a body-weft with the warp in forming a body fabric and to float said body-weft across certain warp threads in forming a medallion-like figure, and means including a figure weft shuttle having a centrally disposed delivery eye for interweaving a figure-weft with said certain warp threads alone to form the figure, the figure-weft floating beyond the lateral borders of the figure, a pair of vertically movable pins carried by the lay, said pins being at opposite sides respectively of the group of figure warps, each pin normally being so positioned that the figure-weft wraps about it just prior to interweaving with the figure warps, and means for retracting each pin to release the float wrapped around it, a weft detector disposed substantially midway between the selvages of the fabric.

Signed by me at Esmond, Rhode Island,
35 this 24th day of April, 1928.

JOSEPH F. MUHEIM.
